COMBINATION LAUNDRY AND SERVICE
WAGON

James J. Gross, Bismarck, Ill.

Application February 28, 1947, Serial No. 731,457

5 Claims. (Cl. 38—104)

1

My invention relates to improvements in combination laundry and service wagons for household use especially.

The primary object of my invention is to provide a simply constructed wagon equipped especially for use as an ironing stand and table and embodying conveniently accessible storage facilities for clothes, or other articles.

Another object is to provide a wagon of the character and for the purpose above set forth embodying an ironing board arranged for easy projection out of a wheeled cabinet for use as desired, and for retraction into said cabinet easily and quickly into hidden stored position when not in use.

Another object is to provide in such a wagon improved brake means for holding the wagon stationary and rendering the same safe to use, particularly in ironing.

Still another object is to provide a wagon for the purposes above set forth which is compactly arranged, easy to handle, and comparatively inexpensive to manufacture and service.

Other and subordinate objects, also comprehended by my invention, together with the precise nature of my improvements, and the manifold advantages thereof, will be readily understood when the succeeding description and claims are read with reference to the drawings, accompanying and forming part of this specification.

In said drawings:

Figure 1 is a view in perspective of my improved combination laundry and service wagon in a preferred embodiment thereof.

Figure 2 is a view in bottom plan.

Figure 3 is a view in vertical longitudinal section.

Figure 4 is a view in vertical transverse section taken on the line 4—4 of Figure 3.

Figure 5 is a view in vertical section taken on the line 5—5 of Figure 3 and drawn to a larger scale with parts broken away.

Figure 6 is a view in plan with the top panel removed and illustrating the ironing board projected and the wings unfolded.

Figure 7 is a view in longitudinal section taken on the line 7—7 of Figure 6.

Figure 8 is a fragmentary view in plan drawn to a larger scale and illustrating the manner in which the wings are unfolded and folded.

Referring now to the drawings by numerals, in the preferred illustrated embodiment thereof, my improved laundry and service wagon comprises a rectangular, horizontal, wheel supported platform 1 including front and rear end cross bars

2

2, 3, side bars 4, an intermediate central cross bar 5, and a platform panel 6 suitably fixed on said bars. Front and rear pairs of wheels 7, 8, of any suitable type, support the platform, with the panel 6 elevated above said wheels for a particular purpose presently seen.

Surmounting the platform 1 is a closed cabinet 9 of the same shape as the platform 1 and which includes front and rear pairs of legs 10, 11 arising from the corners of the platform 1. A bottom panel 12 for the cabinet 9 is supported, in spaced relation to the platform 1, by front and rear cross bars 13, 14, and by side bars 15, the front and rear cross bars 13, 14 extending between the front and rear pairs of legs 10, 11, and the side bars 15 extending between the front and rear legs 10, 11 upon opposite sides of the cabinet with a central cross bar 16 extending between the same. A top panel 17 for the cabinet 1 is supported by front and rear cross bars 18, 19, extending between the pairs of front and rear legs 10, 11, and by side bars 20 extending between the legs 10, 11, upon opposite sides of the cabinet with a central cross bar 21 extending between the same. A horizontal partition panel 22, in the cabinet 9, is spaced below the top panel 17, and supported by front and rear cross bars 23, 24, also extending between the pairs of front and rear legs 10, 11, and by side bars 25, also extending between the front and rear legs 10, 11 upon opposite sides of the cabinet and having an intermediate connecting cross bar 26 extending between the same. Front and rear end wall panels 27, 28, and side wall panels 29 are provided for the cabinet 9.

The space between the top panel 17 and the partition panel 22 provides a storage chamber 30 for an ironing board, presently described, and to which access is provided for by a pair of upper companion doors 31 in the front end wall panel 27 hinged, as at 32, to opposite side edges of said panel to open outwardly in opposition to coil springs 33 connected at one end, as at 34, to said doors with the other ends thereof suitably fixed in said chamber 30, as at 35. The doors 31 are adapted to close an upper front end doorway 36 in the front end panel 27 and front end of the chamber 30 and extending from one leg 10 to the other.

The space between the partition panel 22 and the bottom panel 12 of the cabinet 9 provides a storage chamber 37 for damp clothes, or other articles, and in which a pair of lower drawers 38 are slidably mounted on the bottom panel 12 to be pulled outwardly of one side panel 29. The

3

drawers 38 are guided between front and rear cross guide bars 39, 40 in the chamber 37 and imposed on the panel 12, and a vertical spacer frame 41 provided in the chamber 37 in the transverse center thereof and reinforcing the side panels 29 and the partition panel 22.

The space between the bottom panel 12 of the cabinet 9 and the platform panel 6 is designed to form a rack for suitable baskets, for containing clothes or the like, and which have not been illustrated since the same form, per se, no part of the present invention.

An ironing board 42 is provided in the chamber 30 for endwise sliding and vertical movement to be projected out of the doorway 36 for use of the same, or, retracted into said chamber 30 for storage purposes, and which will now be described.

The ironing board 42 comprises a substantially T-shaped base panel 43 with its wider end slidably fitting between the sides of the doorway 36 and between horizontal side bars 44 extending along the partition panel 22 on top thereof between the front and rear legs 10, 11 upon opposite sides of the cabinet 9. The base panel 43 is provided with a relatively narrower tapering front end section 45 in the longitudinal center thereof and best shown in Figure 6. Surmounting the section 45 is an ironing section 46 relatively narrower than the doorway 36 and centered longitudinally of the base panel 43 with a front tapered nose portion 47 and straight parallel sides 48 behind said portion 47. The ironing section 46 is spaced above the base section 43 by forwardly converging, side spacer bars 49 and a rear abutment forming bar 50, as best shown in Figure 7, a distance less than the height of the doorway 36, and the chamber 30, and for a purpose presently seen. A coil spring 51 attached at one end, as at 52, in the center of a rear cross bar 51' on the panel 43 with its other end attached, as at 53, to a cross bar 54 in the chamber 30, normally serves to retract the ironing board 42 into the cabinet 9 and chamber 30. A pair of triangular, folding, side wings 55 are hinged, as at 56, to the sides 43 of the ironing section 46 to be unfolded outwardly and downwardly into the plane of said section 46 to impart to said section a wedge shape in plan, said wings 55 being suitably hinged to be folded over said section 46 flat against the same, when not in use, as shown in dotted lines in Figure 8. The wings 55 are designed to extend the width of the ironing section 46, at its rear end, to substantially that of the cabinet 9. Ledges 56 are provided on the inner sides of the doors 31, at the upper front corners thereof, to support the wings 55 when said wings are unfolded. A cross cleat 57 is provided on the base section 43 and spaced from the abutment forming bar 50 for a purpose to be explained.

A tongue 58 is provided for pulling the wagon from place to place and which comprises a pair of outer and inner telescopic, tubular sections 59, 60, the outer section 59 being fixed, intermediate its ends, as by a band 61, between the outer ends of a pair of fork forming rods 62 having lateral outturned inner ends 63 journaled in bearings 64 on the front end cross bar 2 of the platform 1 so that said tongue 58 is vertically swingable. A cross rod 65 in the outer end of the section 59 provides for obtaining a firm hand grip on said tongue 58. As best shown in Figure 5, the inner section 60 is endwise slidable with a friction fit in the outer section 59 by means of a lateral handle 64 on said inner section extending out of a longi-

4

tudinal slot 64' in said outer section, and said inner section 60 is provided with an inner end screw plug 66, all for a purpose to be explained. A clip type, resilient latch 67 is provided on the front end of panel 27 of the cabinet 9 for gripping the outer section 59 of the handle 58 to yieldingly latch said handle in upright position, as shown in Figure 1, when the handle is not in use.

A pair of brake levers 68 are pivoted intermediate the ends thereof, as at 69, in notches 70 in the side bars 4 to be swung horizontally, counter-clockwise as viewed in Figure 2, into braking position to apply brake shoes 71 thereon to the front wheels 7 and thus prevent the wagon from creeping or drifting. A brake equalizing bar 72 extends across the bottom of the platform 1 with its ends slidable in slotted guide rails 73 suitably secured to the undersides of the side bars 4 of the platform 1, the arrangement being such that said bar 72 is slidable forwardly and rearwardly of said front wheels 7. A pair of brake applying bars 74 pivoted, as at 75, to said levers 68, and to said equalizing bars 72, as at 76, operatively connect the equalizing bar 72 to the brake levers 68 so that rearward movement of said equalizing bar 72 acts to apply the brake shoes 71, and forward movement of said equalizing bar 72 acts to release said brake shoes. A coil spring 77 having its ends connected to said equalizing bar 72, in the transverse center thereof, and to the rear end bar 3 of the platform 1, as at 78, 79, urges the equalizing bar 72 rearwardly to normally apply the brake shoes 71. A pull cable 80 is anchored at one end in the plug 66, as at 81, and trained under a pulley 82 on the front end cross bar 2 of the platform 1 with its other end attached, as at 83, to the equalizing bar 72, in the transverse center thereof, whereby, when the inner section 60 of the tongue 58 is slid forwardly of said tongue, the brake equalizing lever 72 is pulled forwardly in opposition to the coil spring 77 to cause release of the brake shoes 71 in a manner which will be clear. Thus the brakes are lock applied by frictional engagement of the inner section 60 of the tongue 58 with the outer section 59 of said handle. An end notch 84 may be provided in slot 64' and into which the handle 64 may be swung to positively lock the brake equalizing lever 72 in a forward brake shoe applying position.

As best shown in Figures 3 and 4, when the ironing board 42 is stored in the cabinet 9 and chamber 30, the same rests on the partition panel 22 with the wings 55 folded on top thereof, and the end doors 31 may then be closed to hide said board and close said chamber. To use the ironing board 42, the doors 31 are opened and said board 42 slid forwardly out of the doorway 36 and then elevated so that the abutment forming bar 50 and the cleat 57 straddle the top edge of the doorway 36, and the base panel 43 abuts said edge, in which position of said board, the ironing panel 46 may be adjusted to position the same flush and coplanar with the top panel 17 of the cabinet 9. For adjusting and maintaining the ironing panel 46 in elevated position, a pair of substantially semicircular cams 85, with straight side edges 86 are provided on the opposite ends of a cross shaft 87 journaled in the side bars 25 for operation by an end crank 88 thereon to rotate said cams 85 upwardly through slots 89 in the partition panel 22, such rotation of said cams 85 serving to engage corners thereof, as shown in Figure 7, with the base panel 43 to elevate the rear end of the ironing board 42 until the cross bar 51' engages the top panel 17 and

stops further elevation of the rear end of said ironing board. Further rotation of said cams 85 in the same direction serves to maintain said rear end of the ironing board 42 elevated until the straight edges 86 of the cams 85 are uppermost, at which point, said ironing board 42 may be lowered at its rear end. An aperture 90 is provided in the front end of the section 49 of the ironing board 42, and the tongue 53 is arranged to be inserted in said aperture in a forwardly swung position, as shown in Figure 7, to engage the ironing panel 41 to hold the front end of the ironing board 42 in elevated position with the ironing section 47 flush and coplanar with the top panel 17. When the ironing board 42 has been elevated, as described, the wings 55 may be unfolded onto the ledges 56 of the doors 31 to be supported by said ledges and doors as best shown in Figures 6, 7 and 8. To store the ironing board 42, it is merely necessary to rotate the cams 85 so that the straight edges 86 thereof are uppermost and below the partition panel 22, then tilt the ironing board 42 upwardly at its front end to withdraw the front end of the tongue 48 out of the aperture 90, after which said board 42 may be lowered at its front end, for a purpose which will be clear, and released for retraction into the cabinet 9 and chamber 30 by means of the spring 51 after the wings 55 have been folded onto the ironing section 46 in the manner illustrated in dotted lines in Figure 8.

As will be seen, the ironing 42 being stored as described, the wagon may be used as a serving wagon with the top panel 17 forming a table top adapted to be used for serving purposes.

The foregoing will, it is believed, suffice to impart a clear understanding of my invention, without further explanation.

Manifestly, modifications of the invention described, both as regards combinations of parts and structural details, may be resorted to, without departing from the inventive concept, and right is herein reserved to such modifications as fall within the scope of the appended claims.

What I claim is:

1. A wheel supported cabinet having a pair of upper doors hinged to opposite sides of the cabinet at one end thereof and opening outwardly, a tongue on said end of the cabinet swingable upwardly, an ironing board slidable partway out of said end of the cabinet past the opened doors into projected position, means on said board for interlocking the same with said tongue whereby said tongue when swung upwardly acts as a support for said board, and coacting devices on said doors and board for supporting the board at the sides thereof on said opened doors.

2. A wheel supported cabinet having a pair of

upper doors hinged to opposite sides of the cabinet at one end thereof and opening outwardly, a tongue on said end of the cabinet swingable upwardly, an ironing board slidable partway out of said end of the cabinet past the opened doors into projected position, means on said board for interlocking the same with said tongue whereby said tongue when swung upwardly acts as a support for said board, and coacting devices on said doors and board for supporting the board at the sides thereof on said opened doors, comprising ledges on said doors and wings on said board hinged to fold down onto said ledges.

3. A wheel supported cabinet having a doorway therein, an ironing board slidable partway out of said doorway into projected position and vertically adjustable, spring means opposing sliding of said board out of said doorway, and means on said board for interlocking the same with the upper edge of the doorway by vertical adjustment of said board to lock the same in projected position against retraction by said spring.

4. A wheel supported cabinet having a doorway therein, an ironing board slidable partway out of said doorway into projected position and vertically adjustable, spring means opposing sliding of said board out of said doorway, means on said board for interlocking the same with the upper edge of the doorway by vertical adjustment of said board to lock the same in projected position against retraction by said spring, and rotary means in said cabinet operative from the exterior thereof to adjust said board.

5. A wheel supported cabinet having a pair of upper doors hinged to opposite sides of the cabinet at one end thereof and opening outwardly, a tongue on said end of the cabinet swingable upwardly, an ironing board slidable partway out of said end of the cabinet past the opened doors into projected position, means on said board for interlocking the same with said tongue whereby said tongue when swung upwardly acts as a support for said board, coacting devices on said doors and board for supporting the board at the sides thereof on said opened doors, normally applied wheel brakes, and means on said tongue operative when said board is interlocked with said tongue to release the brakes.

JAMES J. GROSS.
